UNITED STATES PATENT OFFICE.

AUSTIN BROOMFIELD, OF CRAIGS, MISSISSIPPI.

HARROW.

SPECIFICATION forming part of Letters Patent No. 744,715, dated November 24, 1903.

Application filed January 7, 1903. Serial No. 138,165. (No model.)

To all whom it may concern:

Be it known that I, AUSTIN BROOMFIELD, a citizen of the United States, residing at Craigs, in the county of Yazoo and State of Mississippi, have invented new and useful Improvements in Harrows, of which the following is a specification.

My invention relates to new and useful improvements in harrows, and its object is to provide a device of this character which may be readily adjusted to bring the tooth-holding bar to any desired angle in relation to the tongue of the harrow.

Another object is to provide novel means for holding the teeth of the harrow in position upon the bar, whereby they may be readily detached and replaced.

A further object is to employ double harrow-teeth, which may be readily inverted and either end used upon the ground.

With the above and other objects in view the invention consists in providing a tongue to one end of which is pivoted a tooth-holding bar, preferably formed by bending a strip 25 of sheet metal upon itself to form parallel sections. An arm is arranged integral with this bar and extends at right angles therefrom and is adjustably secured to the tongue, thereby permitting said bar to be held at any 30 desired angle to the tongue.

The invention also consists in employing securing-straps each of which is hinged between the sections of the bar and is adapted to swing over the harrow-teeth and clamp the 35 same against said bar, suitable means being employed for securing the straps in clamping position.

The invention also consists in providing a harrow-tooth which comprises a stem and oppositely-extending teeth at the ends thereof. This stem is adapted to be inverted, and either of the teeth can be employed upon the 40 ground.

The invention also consists in the further 45 novel construction and combination of parts hereinafter more fully described and claimed, and illustrated in the accompanying drawings, showing the preferred form of my invention, and in which—

50 Figure 1 is a perspective view of my improved harrow. Fig. 2 is a rear elevation thereof. Fig. 3 is a horizontal section through

one end of the tooth-holding bar of the harrow. Fig. 4 is a detail view of the tooth-secur ing strap. Fig. 5 is a transverse section 55 through the bar of the harrow, and Fig. 6 is a detail view of a harrow-tooth.

Referring to the figures by numerals of reference, 1 is a tongue having handles 2 extending upward therefrom, said handles being braced by means of bars 3, which are connected to a plate 4, secured to the rear end of the tongue. This tongue is pivoted at a point 5 adjacent to the rear end of the central portion of a tooth-carrying bar 6. This bar 65 is preferably formed of a strip of metal bent upon itself to form parallel sections, and said sections are extended forward at one end of the bar to form an arm 7, which embraces the tongue 1 and is adapted to be adjustably secured thereto by means of a pin 8, which may be arranged within any one of a series of apertures 9, formed within said arm.

At desired intervals within the bar 6 are arranged pivot-pins 10, upon each of which is mounted a strap 11, preferably curved longitudinally and having an aperture 12 in its free end for the reception of a securing-bolt 13, adapted to extend between the sections of the bar 6 and engage a plate 14, embracing 80 the rear edge of the bar. The front edge of each of the parallel sections of bar 6 is provided with apertures 15, arranged adjacent to the pivoted pins 10. These recesses are adapted to receive stems 16, having oppositely-extending harrow-teeth 17 formed at the ends thereof. These stems are secured within the recesses by swinging the straps 11 thereover and clamping the same thereagainst by means of the bolts 13, before referred to. When it is desired to remove one or more of the teeth for the purpose of replacing or inverting them, it is merely necessary to loosen the bolt which clamps the securing-strip of said tooth in position. The 95 same can then be readily removed.

It will be seen that this harrow is extremely simple and durable in construction and can be manufactured at slight cost.

In the foregoing description I have shown 100 the preferred form of my invention; but I do not limit myself thereto, as I am aware that modifications may be made therein without departing from the spirit or sacrificing any

of the advantages thereof, and I therefore reserve the right to make such changes as fairly fall within the scope of my invention.

Having thus described the invention, what 5 is claimed as new is—

In a harrow, the combination with parallel recessed strips forming a tooth-carrying bar; of a tooth-holding strap pivotally mounted at one end between said strips and adapted to 10 swing outward therefrom, a plate embracing

the strips, and means engaging said plate and the other end of the strap for holding said strap in retaining position.

In testimony whereof I affix my signature in presence of two witnesses.

AUSTIN BROOMFIELD.
